DESIGN FOR A MOUTHPIECE FOR A SAXOPHONE OR OTHER MUSICAL INSTRUMENT

Clinton A. Runyon, Jr., Chicago, Ill.

Application July 22, 1944, Serial No. 114,518

Term of patent 14 years

(Cl. D56—1)

To all whom it may concern:

Be it known that I, Clinton A. Runyon, Jr., a citizen of the United States, residing at Chicago, in the county of Cook and State of Illinois, have invented a new, original, and ornamental Design for Mouthpiece for a Saxophone or Other Musical Instrument, of which the following is a specification, reference being had to the accompanying drawing, which forms a part thereof.

In the drawing:

Figure 1 is a side elevational view of a mouthpiece for a saxophone or other musical instrument, showing my new design;

Figure 2 is a top plan view;
Figure 3 is a bottom plan view;
Figure 4 is an elevational view of one end of the mouthpiece; and

Figure 5 is an elevational view of the other end of the mouthpiece.

I claim:

The ornamental design for a mouthpiece for a saxophone or other musical instrument, substantially as shown.

CLINTON A. RUNYON, JR.
